ROBERT J. HODGE, OF WEST HAVEN, CONNECTICUT

RAZOR

Application filed December 7, 1929. Serial No. 412,555.

This invention relates to razors and more particularly to the type of safety razors employing means for producing a relative movement between the blade and its holder.

The objects of the invention are to provide a safety razor with a novel means for reciprocating the blade relative to the holder; to provide, for association with such novel means, a series of blades of which the structure of each predetermines the direction of the reciprocating movement of the blades; to provide, as a part of such novel means, symmetrically spaced blade-reciprocating members; and to provide a simple mechanical means for imparting motion to the blade-reciprocating members, the invention consisting in the novel constructions, to be hereinafter described or claimed, for carrying out the above stated objects and such other objects as may hereinafter appear.

The character of the invention may be best understood by reference to one illustrative device embodying the invention and illustrated by the figures in the accompanying drawings in which the Figure 1 is a front elevation of the full device; the Figure 2 is a side elevation thereof; the Figure 3 is a top view thereof; the Figure 4 is a cross-sectional view of the top section of the device; the Figure 5 is a front elevation of the device with the top section removed and the casing and the handle illustrated in cross-section to expose to view the interior parts; the Figure 6 is a view of the under side of the top section; the Figure 7 is a top view of the device with the top section removed; the Figure 8 is a similar view of the device but illustrating the casing in cross-section to expose to view the interior parts; and the Figures 9, 10, and 11, are plan views of razor-blades in series.

The invention is not limited to any specific form of construction and the details of the device may be varied to produce the novel features hereinafter claimed. The device as illustrated however includes a spring-actuated geared mechanism for rotating a shaft presenting an eccentric extremity projecting above the surface of a stationary plate upon which the razor blade is guidingly

supported, the blade having an elongated perforation into which is received the eccentric extremity to impart to the blade a reciprocating motion, but, the manner in which the rotatable shaft engages its eccentric extremity with the blade perforation being an important feature of novelty of the invention, it is immaterial in the broad sense what means may be employed to impart movement to the rotatable shaft.

Referring more particularly to the drawings, the device comprises the hollow stem 1 serving as a handle and fixedly supporting the casing 2 having the stationary plate 3 and the detachable plate or section 4. The casing 2, as illustrated by the Figures 5 and 8, is a box-like structure of which the rectangular stationary plate 3, best illustrated by the Figure 7, is the cover having the downwardly bent ends 5, illustrated in dotted lines by the Figure 7 and in cross-section by the Figures 5 and 8, and setting within and riveted to the end portions 6 of the casing. The longer sides of the stationary plate 3 are each provided with guard-teeth 7, and the top surface of the plate 3 is provided with the substantially rectangular central projection 8 having a plurality of parallel side walls and having the tapped bore 9, the plate 3 also having the spaced bores 10 and the larger spaced bores 11, as illustrated by the Figure 6. The floor 12 of the casing 2 is provided with a central bore 13 communicating with the interior of the stem 1, the floor 12 being also provided with the spaced bores 14 and the spaced bores 15 in axial alignment with the spaced bores 10 and the spaced bores 11, respectively, as illustrated by the Figure 5. Within the casing 2 is the gearing comprising, first, the large gear wheel 16 fixed to the shaft which engages the central bore 13, the shaft also carrying the disk 17 fixed thereto and occupying a position within the stem 1; second, the small gear wheels 18 and 19 intermeshed with the gear 16 and each fixed to a different one of the shafts engaging the spaced axially aligned bores 10 and 14, respectively; third, the large spaced gear wheels 20 and 21 respectively fixed to the shafts of the small gears 18 and 19; and

fourth, the lantern wheels 22 respectively intermeshed with the gear wheels 20 and 21, each lantern wheel being provided with a shaft at its lower end engaging one of the spaced bores 15 in the floor 12 of the casing 2 that are in axial alignment with the larger spaced bores 11, the upper end of each lantern wheel 22 being provided with an enlarged shaft section 23 for engagement with in one of the large spaced bores 11 and lying substantially flush with the outer surface of the stationary plate 3 and presenting above that surface an eccentric extension 24, one eccentric extension 24 of the shaft 23 being similarly positioned relative to the shaft 23 as the eccentric extension of the other shaft 23 is to its shaft, as illustrated by the Figures 5 and 7. The free end of the hollow stem 1 has its annular edge provided with the ratchet teeth 25. A knob 26 is provided with a reduced inner end 27 forming a shoulder provided with the ratchet teeth 28 for interengagement with the teeth 25, the reduced end 27 being rotatably fitted within the free end of the stem 1. Both the disk 17 and the reduced end 27 are provided with a hook element 29 for engagement by the opposite ends of a coiled spring 30 exerting a contracting tension to maintain the knob 26 within the free end of the stem 1, as illustrated by the Figure 5. The detachable plate 4 has an under surface 31 provided with a central rectangular depression 32 provided with a tapped bore extending through the plate, the under surface 31 also having the spaced annular depressions 33 and the feet 34. The outer surface of the plate 4 has a central annular depression 35 surrounding the tapped bore 37 for the accommodation of the coiled spring 36, the bore 37 accommodating the thumb-screw 38 having a shoulder against which the spring 36 exerts a tension, as illustrated by the Figure 4. The blades 39, 40, and 41, each has a central perforation 42 of substantially rectangular form, but of varied long and short diameters, and they also have spaced elongated companion slots 43, 43A, and 43B, respectively, the central perforation of each blade being differently shaped and the slots of each blade extending in a different direction, as illustrated by the Figures 9, 10, and 11, the razor is thus provided with a blade series for a purpose to be directly explained.

55 In operation, the blade 39, for instance, having the longer diameter than that of the projection 8, is placed upon the stationary plate 3 so that both of the longer sides of the perforation 42 fit over and simultaneously engage against the longer sides of the projection 8 for a relative sliding movement, and the spaced longitudinal slots 43 each receive an eccentric extension 24 of an enlarged shaft 23. The detachable plate 4 is then placed over the blade so that the rectan-

gular depression 32 fits over and is positioned by the projection 8, the spaced annular depressions 33 axially registering with the enlarged shaft 23 and allowing a limited freedom of movement therein of the eccentric extensions 24, as the feet 34, engaging marginal portions of the stationary plate 3, maintains a spaced relation of the detachable and stationary plates. The thumb-screw 38 is then screwed into the tapped bores 37 and 9 and down against the end of the shaft of the large gear wheel 16 to hold the shaft against rotation. The knob 26 is then relatively turned clockwise as regards the free end of the stem 1, the interengaging ratchet teeth of both stem and knob permitting a step by step rotary movement of the knob within the stem and against both axial retracting and winding tensions of the spring 30. The spring 30 being thus wound up, the thumb-screw 38 is slightly loosened to release the geared mechanism, the spring 36 maintaining the detachable plate 4 in close engagement with the stationary plate 3. The mechanism responding to the tension of the unwinding spring immediately operates the enlarged shafts 23 which in turn operate the eccentric extensions 24 rotatably within the slots 43 of the blade 39. The slots 43 being too narrow to include therein the radial sweep of the eccentric extensions 24 the blade is thereby reciprocated along the short axis of the slots and over the stationary plate 3 toward and away from the toothed edges of that plate, the central projection smoothly guiding such movement of the blade. Should a longitudinal reciprocating movement of a blade be desired, the second blade 40 of the blade series may take the place of the blade 39. The blade 40, having a shorter but wider perforation than that of the blade 39, is placed upon the stationary plate 3 for simultaneous engagement of both of its short sides of the perforation 42 with the short sides of the projection 8, the spaced transverse slots 43A each receiving an eccentric extension 24 of an enlarged shaft 23. By means of the rotating eccentric extensions 24 within the slots 43A the blade is reciprocated in the manner above explained, but in a longitudinal direction; for the movement of the blade must be along the short axis of the slots. Other blades, as for instance the blade 41, may be included within the blade series to be reciprocated, relative to the stationary plate 3, in other directions, the oblique slots 43B and the oblique corner edges 44 of the central perforation 42 of the blade 41 being adapted to simultaneously and slidingly engage diagonally opposite oblique walls 45 of the projection 8. The blade thus provides two additional blade-reciprocating directions, the particular direction of the reciprocating movement of the blade 41 depending upon 130

which side surface of the blade is placed against the stationary plate 3.

I claim:—

1. A razor comprising a stationary rectangular plate of which the parallel longer edges are provided with guard teeth; a central blade-guiding projection provided by the plate, the projection having opposing parallel side walls; a blade provided with a blade-guiding central perforation having opposing parallel edges for sliding engagement with the parallel walls of the projection; companion slots provided by the blade, each slot having long and short axes having a center spaced equi-distant from the center of the blade; a detachable plate spaced from and detachably secured to the stationary plate and overlying the mounted blade; and means for imparting a reciprocating movement to the blade along the short axes of the slots, the means comprising rotatable shafts having ends journaled within bores provided by the stationary plate concentric with the centers of the axes of the slots of the mounted blade, both shafts having eccentric extensions each engageable within a slot of the blade to move the blade along the short axes of the slots.
2. A razor comprising a stationary rectangular plate of which the parallel longer edges are provided with guard teeth; a central blade-guiding projection provided by the plate, the projection having a plurality of opposing parallel side walls; a blade provided with a blade-guiding central perforation having opposing parallel edges for sliding engagement with certain of the parallel walls of the projection; companion slots provided by the blade, each slot having long and short axes having a common center spaced equi-distant from the center of the blade; a detachable plate spaced from and detachably secured to the stationary plate and overlying the mounted blade; and means for imparting a reciprocating movement to the blade along the short axes of the slots, the means comprising rotatable shafts having ends journaled within bores provided by the stationary plate concentric with the centers of the axes of the slots of the mounted blade, both shafts having eccentric extensions, each engageable with a slot of the blade, the guiding means of the stationary plate and the radial position of the slots of the mounted blade cooperating to predetermine the direction of the reciprocating movement of the blade.

3. A mechanical razor comprising a toothed edge stationary rectangular plate having an underlying box structure supported by a fixed hollow handle in perpendicular relation thereto; a central blade-guiding projection provided by the plate, the projection having a plurality of opposing parallel side walls; a blade provided with a blade-guid-

ing central perforation having opposing parallel edges for sliding engagement with certain of the parallel walls of the projection; companion slots provided by the blade, each slot having long and short axes having a common center spaced equi-distant from the center of the blade; a detachable plate spaced from and detachably secured to the stationary plate and overlying the mounted blade; and mechanism for imparting a reciprocating movement to the blade along the short axes of the slots, the mechanism comprising rotatable shafts having ends journaled within bores provided by the stationary plate and the box structure axially concentric with the centers of the axes of the slots of the mounted blade, both shafts having eccentric extensions, each engageable within a slot of the blade, the shafts being a part of a geared connection provided within the box structure and actuated by a coiled spring provided within the hollow handle with one spring end connected with and maintaining a rotatable knob mounted upon the free end of the handle, the engaging faces of the handle extremity and the knob having ratchet-teeth formation for interengagement, and the securing means of the plates providing a detent to the mechanism.
